UNITED STATES PATENT OFFICE.

HARRY J. SCHMITT, OF BROOKLYN, NEW YORK, ASSIGNOR TO WILLIAM R. NOE & SONS, A COPARTNERSHIP, OF NEW YORK, N. Y.

DESIGN FOR A SHADE FOR AN ELECTRIC LAMP.

Application filed May 7, 1926. Serial No. 17,602. Term of patent 7 years.

To all whom it may concern:

Be it known that I, HARRY J. SCHMITT, a citizen of the United States, residing at Brooklyn, in the county of Kings and State of New York, have invented a new, original, and ornamental Design for a Shade for Electric Lamps, of which the following is a specification, reference being had to the accompanying drawing, forming part thereof, in which—

Fig. 1 is a top view showing the contour of the shade;

Fig. 2 is a front view showing my new design.

I claim—

The ornamental design for a shade for an electric lamp, as shown.

HARRY J. SCHMITT.
